J. F. ROSE

AUTOMATIC BEARING ADJUSTER

Filed March 21, 1921

INVENTOR
J. F. ROSE
BY
Wm. M. Rose
ATTORNEYS

UNITED STATES PATENT OFFICE.

JOHN F. ROSE, OF MOLINE, ILLINOIS.

AUTOMATIC BEARING ADJUSTER.

Application filed March 21, 1921. Serial No. 453,932.

To all whom it may concern:

Be it known that I, JOHN F. ROSE, a citizen of the United States, and a resident of Moline, in the county of Rock Island and State of Illinois, have invented a new and useful Improvement in Automatic Bearing Adjusters, of which the following is a full, clear, and exact description.

My invention relates to improvements in bearing adjusters, and it consists in the combinations, constructions, and arrangements herein described and claimed.

An object of my invention is to provide a device that is adapted to be applied to a bearing and is automatically operated to adjust the parts of the bearing relatively in order to compensate for wear on the bearing and on a member journaled therein.

A further object of my invention is to provide a device of the character described in which the adjustment of the parts of the bearing is effected by spring actuated means.

A further object of my invention is to provide a device of the character described in which bearing members are maintained in constantly adjusted relative positions to operatively support a shaft, or the like, without shims or spacing members of various thicknesses being required.

A further object of my invention is to provide a device of the character described that is adapted to be applied to an ordinary bearing without extensive changes, if any, being required in the usual construction of the latter.

A further object of my invention is to provide a device of the character described that is simple in construction, thoroughly effective, for the purpose intended, and practical commercially.

Other objects and advantages will appear in the following specification, and the novel features of the invention will be particularly pointed out in the appended claim.

My invention is illustrated in the accompanying drawings forming part of this application, in which—

Figure 1 is a side elevation of the device applied to a bearing,

Figure 2 is a top plan view of the device operatively applied, and

Figures 3, 4 and 5 are detail views in elevation of elements of the device.

In carrying out my invention, I make use of a bearing, such as denoted generally at 1, that comprises cooperating semi-cylindrical

bearing members 2 and 3, the bearing member 2 being provided with an integral connector 4. The members 2 and 3 are each formed with cooperating diametrically opposed lug extensions 5—5 and 6—6. Each lug extension 5 is provided with an opening 7 therethrough aligned with a similar opening 8 through the corresponding lug extension 6 and means are projected through the aligned openings and engage the lug extensions to maintain the members 2 and 3 in adjusted positions to support a shaft 9, while permitting free functional movement of the latter.

The means ordinarily provided to maintain the bearing members 2 and 3 in position to support a shaft are not adjusted automatically and as wear on the relatively moving parts ensues, the shaft becomes loose in its bearing and the strain on the parts is increased, thereby tending to shorten the life of the parts in service. In the embodiment of the invention illustrated, I provide means for maintaining the bearings 2 and 3 constantly in position to support a shaft for rotation without play between the relatively moving parts being permitted on account of wear on such parts. To this end, bolts 10—10 are projected through the aligned openings in the lug extensions and are held against rotation by reason of the engagement of flattened portions 11—11 of heads 12—12 thereof with the adjacent sides of the connector 4. Each bolt is arranged with its shank projecting beyond the lug extension and provided with a screw thread 13 of relatively long pitch. A sleeve or thimble 14 is threaded interiorly for engagement with the threaded end portion of the bolt and the initial adjustment of the bearing member 3 relative to the bearing member 2 is effected by manually operating the retaining sleeve 14. The retaining sleeve 14 has an outwardly extending flange 15 at a spaced distance from the end thereof abutting the lug extension. A spiral spring 16 is disposed on the sleeve 14 and one end thereof is secured at 17 in an opening through the flange 15. Since the flange 15 is spaced from the upper wall of the adjacent lug extension, the end portion of the spring 16 will not be clamped between the flange and the lug extension 6 so as to prevent rotation of the sleeve. An adjusting washer 18 is placed on the bolt 10 and has a flange 19 to which the adjacent end of the spring 16 is secured, as at 20.

From the foregoing description of the various parts of the device, the operation thereof may be readily understood. The bearing member 3 is adjusted relative to the bearing member 2 by means of the threaded sleeves. Each spring 16 is then placed under torsional stress by turning the adjusting washer 18 and will be maintained in that condition when each adjusting washer is 10 locked in position, as by means of a cotter pin 21 projected through a transverse opening 22 in the bolt 10 and engaging diametrically disposed grooves 23 in the upper surface of the adjusting washer. The bolts are 15 held against rotation on account of the engagement of the heads thereof with the adjacent portions of the connector 4 and the adjusting washers are locked against rotation. As wear on the relatively moving 20 parts ensues, the space between the adjacent portions of the leg extensions is lessened and the movement of these members together permits the sleeves to be turned in response to the torsional thrust of the springs 16—16 25 so that the bearing members 2 and 3 will be constantly maintained in adjusted relative

positions to support a shaft, with the necessity for providing shims or other spacing members, of various thicknesses obviated.

The device is simple in construction, is 30 thoroughly effective for the purpose intended, and is not likely to get out of order easily.

I claim:

In a device of the character described, a 35 threaded bolt having an opening extending transversely therethrough and adjacent the outer end thereof, a sleeve having an interiorly threaded bore arranged to receive said threaded bolt, said sleeve having a radial 40 flange on the peripheral wall thereof, an adjustable washer having radial grooves on the upper face thereof, a torsion spring arranged to lie concentric with said sleeve on said bolt and engage said flange at one end 45 and said washer at the other end, and a pin projected through the opening in said bolt and arranged to engage the grooves in said washer to normally prevent the rotation of said washer on said bolt.

JOHN F. ROSE.
